SHOE LAST

George Heinerich Barge, Jamaica, N. Y., assignor,
by mesne assignments, to United Shoe Machinery Corporation, Paterson, N. J., a corporation of New Jersey

Application August 10, 1936, Serial No. 95,219

6 Claims. (Cl. 12—128)

This invention relates to shoe lasts and particularly to shoe lasts employed in the repair of women's shoes, wherein a new sole is attached to the upper part of the shoe by being cemented thereto.

The shoe sole attaching operation is usually carried out by means of a small hand-operated press in which the shoe is supported under pressure until the cement is thoroughly dry and the sole thereby securely fixed to the shoe upper. In order to bring all portions of the sole into contact with the shoe upper and to obtain a uniform distribution of pressure over the entire area of the sole while the cement is drying and thereby effect a good attachment of the sole to the upper, the shoe must be supported by a last conforming accurately to the shape of the shoe and particularly to the shape of the arch or shank portion, which varies according to the style of the shoe as determined by the height of the heel. Obviously, the shoe last equipment required for the repair of shoes is extensive, for it must be sufficient for the resoling of all sizes of shoes of each style, or, in other words, it must comprise a pair of lasts for each size of each style of shoes. Women's shoes generally range from size 3 to size 8, there being several widths of each size, and there are at least four different styles or heel heights, each with a different arch contour, so that disregarding width variations for each size of shoe a minimum of six pairs of lasts for each style of shoe is required.

In its broader aspects, the present invention contemplates a last of given size and shape and interchangeable means selectively cooperable therewith to provide a last entirely of different size and shape. More specifically, the invention provides for the combination with a shoe last having an arch or shank portion shaped to fit the arch of one style of shoe, of a plurality of quick detachable shaped inserts or arch supports selectively attachable thereto to adapt the last to fit any one of several styles of shoes each having differently shaped arches.

In the accompanying drawings, the invention has been shown merely by way of example and in preferred form and obviously many variations and modifications may be made therein without departing from the spirit and scope of the invention. It is to be understood, therefore, that the invention is not limited to any specific form or embodiment except insofar as such limitations are specified in the appended claims.

55 Referring to the drawings:

Fig. 1 is a side elevation, partly broken away, of a shoe supported in a shoe press;

Fig. 2 is a perspective view of a last equipped with one of the arch supporting inserts;

Figs. 3 and 4 are top plan views of a pair of lasts equipped each with an arch supporting insert;

Fig. 5 is a side elevation of a shoe last fitted in a shoe (shown in phantom) for which it is particularly shaped;

Fig. 6 is a view similar to Fig. 5, showing the last and an arch supporting insert adapting it to a style of shoe different from that for which it is particularly shaped;

Fig. 7 is a view similar to Figs. 5 and 6, but showing the last with a different arch supporting insert to adapt it to still another style of shoe;

Fig. 8 is a perspective view of one of the arch supporting inserts;

Fig. 9 is a sectional view taken on the line 9—9 of Fig. 6;

Fig. 10 is a side elevation of a different form of last, showing one of the arch supporting inserts associated therewith; and

Fig. 11 is a sectional view taken on the line 11—11 of Fig. 10.

In the accompanying drawings, and referring particularly to Fig. 1, the shoe press shown is substantially like that disclosed in U. S. Patent No. 1,901,546, comprising a base 1, which is hollow or dish-shaped to serve as a reservoir for water, covered with a flexible shoe supporting pad 2 formed by a rubber diaphragm 3 and an overlying leather covering 4, the latter protecting the diaphragm from wear and possible rupture when the shoe 5 thereon is placed under pressure. In the compartment 6, located on the underside of the base, there is arranged an electrical heating element thermostatically controlled to maintain the water within the hollow base at the desired temperature at all times. When the press is in use, the water in the base being displaceable allows the pad to conform to the shape of the shoe sole and the water forms a substantially rigid medium when under pressure, which, due to its hydrostatic and heat conducting properties, distributes pressure and heat uniformly over the entire area of the sole. The press shown is particularly adapted for attaching half-soles to shoes and the rear edge 7 of the pad 2 stretches over the base 1 of the press and turns downwardly so that the heel of the shoe is unsupported and the arch rests directly on the pad.

The means for pressing the shoe 5 firmly down on the pad 2 comprises the pressure distributing arm or lever 8 pivotally mounted on the base 1,

as at 9, at the forward end of the press and when in operative position extending fore-and-aft over the pad 2, as shown. Near its lower edge, the arm 8 is formed with a plurality of apertures 10 adapted to accommodate a pin 11 by which a post 12 is suspended for engagement with the gooseneck pressure column 13 of the metal last 14, so formed to transmit pressure uniformly throughout the last, the pin 11 being positionable in different apertures 10 to locate the post 12 properly to cooperate with lasts for shoes of different size. The bell-crank lever 15 is pivotally mounted on the upper edge of the arm 8 to rock about the pin 16 and its short arm 17 is formed with a series of notches 18 to receive the bail or link 19 connecting the ends of a pair of springs 20, the opposite ends of which are anchored by brackets 21 secured to the base 1 and which springs, when placed under tension by rocking the bell-crank lever 15, exert pressure which is distributed over the length of the shoe 5 by the arm 8 and through the medium of the water in the base over the entire area of the shoe sole. In order to maintain the bell-crank lever 15 in any position to which it is rocked, the latch 22, pivoted at the free end of the short arm 17 of the lever, as at 23, is provided to engage in one of the series of notches 24 formed on the upper edge of the arm 8, the latch riding freely from one notch to another when the bell-crank lever is rocked counter-clockwise, but engaging in one of the notches to resist the pull of the tensioned springs 20 tending to rock the lever in the opposite direction.

The shoe last 14, shown in Figs. 1 to 7, is a well known type of metal last designed to support the toe and arch or shank portions of the shoe. The last 14 is shaped particularly to fit a high or spike heeled shoe as shown in Fig. 5, having a toe portion 25 and an extended shank portion 26 whose under surfaces conform accurately to the shape of the toe and arch portions of the shoe. However, if used with a lower heel, say a Baby French heel, Fig. 6, or a Cuban heel, Fig. 7, the entire arch of the shoe will be unsupported by the last and in the sole attaching operation the arch of the shoe will yield under pressure and a poor, if not entirely unsuccessful, attachment of the shank portion of the sole with the arch of the shoe will result.

According to the present invention, paired arch supporting inserts 27 are provided, each equipped with a spring steel clip 28 having a turned up end 29 and a horizontal portion 30 embedded therein, as best shown in Figs. 9 and 11. The portion 30 of the clip 28 emerges preferably from the outer side of the insert 27 and is bent upwardly with a vertical portion 31 thereof in engagement with a lateral spacing projection 32 formed on the side of the insert and which provides lateral freedom of movement for the proper fitting of the insert to the last shanks 26, which vary slightly in width in different sized lasts. Above the upper surface 33 of the insert 27, the clip 28 is bent at substantially right angles so that a horizontal arm or portion 34 thereof extends entirely across the top of the insert in spaced relation thereto, and its free end 35 is slightly upturned to facilitate its attachment to the shank extension 26 of the last 14, the upper surface of which is formed with a transverse groove 36 to receive the portion 34 of the clip. The upper surface 33 of each of the inserts 27 is formed so as to correspond to the contour of the under surface of the shank portion 26 of the last

to which it is to be attached; while the shape of the lower surface 37 of each insert is determined by the contour of the arch of the style of shoe for which it is adapted, as clearly shown by a comparison of the inserts shown in Figs. 6 and 7. 5

A modification of the invention showing its application to a wooden last is shown in Figs. 10 and 11. According to this embodiment of the invention, a wooden last 38 may be formed with a transverse opening 39 wherein there is fitted a metal sleeve 40 adapted to receive the overlying attaching arm 34 of the spring clip 28. With this very simple modification, wooden lasts constituting a part of existing repair equipment may be converted for use with the same inserts 27 15 that are provided for use with the metal lasts 14.

It is pointed out that the inserts 27 may be formed of any material suitably rigid to give adequate support to the arch during the sole attaching operation. Hard rubber inserts are 20 preferable, however, for the reason that their slight compressability adapts a single pair of inserts for use with all six different sizes of shoes of a given style. The inserts are formed so that they are slightly wider than the arch of the 25 smallest (size 3) shoe, but not so large that they may not be readily inserted into the shoe. On the other hand, the width of the insert is slightly less than the width of the arch of the largest (size 8) shoe, but when under pressure during the sole 30 cementing operation the insert is compressed and the rubber displaced laterally so that its width is substantially equal to the width of the arch of the shoe. Hence, by the present invention the required shoe last equipment for repairing shoes is reduced to a single set of six pairs of lasts 14 for high heeled shoes and three pairs of arch supporting inserts 27 to adapt the lasts to shoes having lower heels. 35

As already stated, a preferred embodiment of 40 the invention has been shown and described by way of example, but the invention is not limited to such embodiment alone. For example, it is within the scope of the invention to employ interchangeable shaped inserts or attachments to 45 alter the size or shape, or both, of a basic shoe supporting form in any localized area thereof or in its entirety. Hence, the invention is not limited to any specific form or embodiment except insofar as such limitations appear in the appended claims. 50

Having thus described my invention, what I claim is:

1. The combination with a shoe last comprising an integral structure formed with toe and 55 shank portions shaped to conform to the forepart and shank of a shoe having a heel of maximum height to support said portions of the shoe under pressure for the attachment of a sole to the shoe upper by cement, of a member shaped to conform 60 to the shank portion of a shoe of lesser heel height and of different contour than the shank portion of the last and being constructed and arranged to be attached to the last to underlie the shank portion thereof to support the shank of 65 the shoe when pressure is exerted thereon.

2. The combination with a shoe last comprising an integral structure formed with toe and shank portions shaped to conform to the forepart and shank of a shoe having a heel of maximum height to support said portions of the shoe under pressure for the attachment of a sole to the shoe upper by cement, of a quick-detachable member shaped to conform to the shank portion of a shoe of lesser heel height and of different 70

contour than the shank portion of the last and being constructed and arranged to be attached to the last to underlie the shank portion thereof to support the shank of the shoe when pressure is exerted thereon.

3. The combination with a shoe last comprising an integral structure formed with toe and shank portions shaped to conform to the forepart and shank of a shoe having a heel of maximum height to support said portions of the shoe under pressure for the attachment of a sole to the shoe upper by cement, of a member shaped to conform to the shank portion of a shoe of lesser heel height and of different contour than the shank portion of the last and being formed with a spring clip adapted to engage in a recess formed in the shank portion of the last to attach the member thereto and locate it in proper position underlying the shank portion of the last to support the shank of the shoe when pressure is exerted thereon.

4. A shoe shank supporting insert for use with a shoe sole supporting last having a shank portion shaped to conform to the shank portion of a shoe of maximum heel height to adapt the last for use with a shoe having a lesser heel height and a shank of different contour than the shank portion of the last, comprising a member formed with one surface shaped to correspond to the

shape of the shank supporting surface of the last and another surface corresponding to the shape of the shank of the shoe of lesser heel height and different shank contour which it is adapted to fit, and means for attaching said member to the last. 5

5. A shoe shank supporting insert according to claim 4, characterized by the fact that the insert is adapted for use with a plurality of lasts adapted to fit different sizes of shoes of the same heel height, the shanks of which vary in width 10 according to the size of the shoe, and further characterized by the fact that said attaching means is formed for the attachment of said member to any one of said lasts in proper position relative thereto. 15

6. A shoe shank insert according to claim 4, characterized by the fact that the insert is formed of rubber and adapted for use with a plurality of lasts adapted to fit different sizes of shoes of the same heel height, the shanks of 20 which vary in width according to the size of the shoe and the rubber insert being compressible and displaceable to accommodate itself to the width of the shank, and further characterized by the fact that the attaching means is in the form 25 of a spring clip anchored to the insert and engageable in a recess formed in the last.

GEORGE HEINERICH BARGE
